UNITED STATES PATENT OFFICE.

ABBE SPRUNG AND HANS C. BOOS, OF NEW YORK, N. Y.

DESIGN FOR A PAPER CUP.

48,834.

Specification for Design.

Patented Apr. 4, 1916.

Application filed July 3, 1914. Serial No. 848,948. Term of patent 7 years.

To all whom it may concern:

Be it known that we, ABBE SPRUNG and HANS C. Boos, both citizens of the United States, and residing at New York, in the county and State of New York, have invented a new, original, and ornamental Design for Paper Cups, of which the following is a specification, reference being had to the accompanying drawing, forming part thereof.

The figure is an elevational view of a paper cup, showing our new design.

We claim:

The ornamental design for a paper cup as shown.

ABBE SPRUNG.
HANS C. BOOS.

Witnesses:

WARREN E. WILLIS,
FRED. ROEGER.
